UNITED STATES PATENT OFFICE

WILLIAM H. KLEINHAIMER, OF SAN FRANCISCO, CALIFORNIA

WASHING MACHINE

Application filed September 29, 1925, Serial No. 59,280. Renewed November 11, 1929.

The invention relates to improvements in washing machines adapted to be used to wash clothes in stationary laundry trays, and refers particularly to improvements in the impeller and impeller driving mechanism. An object of the invention is to provide a washing machine in which the impeller may be easily disconnected from the driving mechanism.

10 Another object of the invention is to provide a washing machine for use in connection with a laundry tray in which the driving bar for the impeller, which is located in the tray, may be readily removed to facilitate the removal of laundry from the tray.

Another object of the invention is to provide a washing machine in which the impeller may be disconnected from the driving mechanism without removal of the driving bar.

20 Another object of the invention is to provide a portable washing machine in which a thrust bearing is provided for the impeller.

25 A further object of the invention is to provide a portable washing machine having the above objects and which is easily and quickly assembled and disassembled.

The invention possesses other advantageous features, some of which, with the foregoing, will be set forth at length in the following description, where I shall outline in full that form of the invention which I have selected for illustration in the drawings accompanying and forming part of the present specification. In said drawings I have shown one form of washing machine embodying the improvements of my invention, but it is to be understood that I do not limit myself to such 30 form, since the invention, as set forth in the claims, may be embodied in a plurality of forms.

In the drawings:

Figure 1 is an elevation of the impeller and associated driving means which form the 40 subject of my invention, parts of the hollow arm being broken away to reduce the size of the figure, and parts of the impeller being shown in section.

45 Fig. 2 is a top or plan view of part of the

hollow arm showing the latch for holding the driving bar in upper position.

Figure 3 is a horizontal section taken on the plane as indicated by the section line 3—3 of Figure 1.

The improvements of my invention relate to washing machines of the type described in the application of Frank B. Morehouse and Frank Haase, Ser. No. 667,635, filed Oct. 10, 1923. The washing machine therein described is of the portable type which is adapted to be removably attached to stationary laundry trays of the well-known kind. The washing machine is equipped with an impeller for placement in one of the trays to agitate the water and laundry therein. A driving bar extends vertically down through the impeller from a hollow arm containing the driving mechanism. The hollow arm overhangs the laundry tray from its point of attachment to one of the side walls thereof, and the driving mechanism it contains usually comprises a reciprocating rack driven by an electric motor for rotating the driving bar alternately in opposite directions. It is sometimes desirable in the operation of this type of machine to disconnect the impeller from the driving mechanism while the driving mechanism is in motion. This has heretofore been accomplished by withdrawing the driving bar vertically from the impeller and from the hollow arm. To connect the impeller with the driving mechanism again, it was necessary to reinsert the driving bar through the hollow arm and into the impeller. This was not an easy operation, particularly if the impeller was out of sight beneath a tray full of laundry and especially if its position had been slightly altered from that at the time of withdrawal of the driving bar. Also, in the previous type of machine, the driving bar extended through the impeller and rested on the bottom wall of the laundry tray. The central supporting boss of the impeller, surrounding the driving bar, also rested on the bottom wall of the laundry tray and the rotation of the impeller and of the driving bar tended to wear a depression in the bottom wall of the laundry tray.

To overcome the difficulties mentioned 50

above, I have provided a driving bar which need not be entirely withdrawn from the impeller in order to disconnect the impeller from the driving means, and in addition I have provided a resting plate or bearing plate to be positioned under the impeller and under the driving bar to prevent them from coming into rotational contact with the bottom wall of the laundry tray.

10 In the embodiment of my improvement shown herein, the hollow arm 2 extending from the point of support of the washing machine on the laundry trays forms a housing for a driving gear 3, shown in dotted lines. 15 The driving gear is suitably journaled in the hollow arm and is driven by appropriate means such as the rack bar 4 which is reciprocated by an electric motor and intermediate gearing, not shown. The driving gear is 20 provided with a non-circular central bore, preferably of rectangular section, for receiving the square portion of a driving bar 6. The driving bar preferably comprises an upper square portion 5 for engagement with the 25 driving gear, a central cylindrical portion 7 of a diameter equal to or less than the side of the square portion, and a lower square portion 10 of the same cross section as the upper square portion. A circumferential 30 groove 8 is provided at the junction of the central cylindrical portion 7 and the upper square portion 5.

An impeller 9 having impeller blades 11 is mounted on the lower end of the driving bar 35 by means of a square central aperture, allowing for axial movement of the bar with respect to the impeller, but positive rotation of the impeller with the driving bar. The lower end of the central aperture in the impeller enlarges into a peripheral groove 12 of circular cross section, which is narrowed by means of the shoulder 13 into a smaller circular passage.

Means are provided for preventing the impeller from bearing on the lower wall of the laundry tray and for keeping the driving bar positioned somewhat above the bottom of the impeller. A detachable resting plate is preferably used for this purpose, and the resting 50 plate in its preferred form includes a bearing disc or plate 17 of sufficient area to form a solid bearing on the lower wall of the laundry tray. Formed integrally with the bearing disc 17 is a central hub 19 adapted to be 55 inserted into the aperture in the lower end of the impeller, and provided with a peripheral groove 14. A spring ring 16, of the well-known kind, is seated in the groove 14 in the resting plate and is of such size and tension 60 that it may readily be inserted through the constricted passage formed by the shoulder 13, but will expand in the recess 12 after passage through the aperture formed by the shoulder 13 and will bear on the upper surface of the shoulder.

Inasmuch as the driving bar has a sliding fit in the impeller, and in the driving gear 3, it may easily be shifted in an axial direction. The shifting is usually accomplished by grasping the top of the driving bar with the hand and exerting an upward pull. It will usually be retained by gravity in its lower axial position, and will contact with the hub 19 of the resting plate. Means are provided for retaining the driving bar in upper axially shifted position. The hollow arm 2 is provided with a boss 19 on its upper surface, and an extension of the boss 19 is provided as a mounting for a latch 22. The latch is pivoted to the boss 19 by means of the pin 21, and is provided with a notch 23 of generally semi-circular contour.

With the mechanism as shown in the drawings, the continuous rotation in alternate directions of the driving gear 3 will produce a corresponding movement of the driving bar 6, which in turn will impart its motion to the impeller 11. In order to disconnect the impeller from the driving gear 3, it is necessary merely to lift or axially displace the driving bar until the upper square portion is withdrawn from engagement with the gear 3 and the cylindrical portion 7 is lifted into the gear. The driving gear 3 may then rotate about the cylindrical portion 7 without imparting its motion to the driving bar. If it is desired to retain the driving bar in its upper, disengaged position, the latch 22 is moved from its position shown in full lines in Fig. 2 to its position shown in dotted lines in the same figure. In the dotted line position, the semi-circular notch 23 of the latch engages the groove 8 in the driving bar and retains the driving bar in position. The driving bar is preferably proportioned so that when the reduced cylindrical portion 7 is centered in the driving gear 3, the lower end of the driving bar will still be in engagement with the impeller, and will therefore facilitate the return of the driving bar to its lower position.

The detachable resting plate 17 is preferably of sufficient area so that the friction between the bearing disc and the lower wall 18 of the laundry tray will insure the resting plate remaining stationary despite the motion of the impeller. Also, the spring ring 16 is of such tension, that the hub 19 may easily be inserted into the aperture 12 at the bottom of the impeller, and will be retained there with sufficient firmness to prevent accidental dislodgment of the resting plate, but will permit the resting plate to be easily withdrawn when it is desired to do so. It will be noted that in addition to providing a stationary thrust bearing for the impeller, the hub of the resting plate also acts as a stop for the driving bar when the driving bar is in its lower or engaged position.

It will be appreciated from the foregoing

description, that I have provided means in a portable washing machine by which the impeller may be disconnected from the driving mechanism without total withdrawal of the driving bar from the impeller or from the driving gear, and that I have also provided a stationary bearing for the lower end of the driving bar and for the impeller, by means of which the impeller and driving bar are prevented from wearing depressions in the bottom wall of the laundry tray.

I claim:

1. In a washing machine, a housing, an impeller, a continuously operating driving gear mounted in said housing and provided with a non-circular aperture therethrough, an axially shiftable driving shaft having a non-circular portion and a reduced cylindrical portion threaded through said gear, said non-circular portion engaging the gear in one position of the shaft, and said cylindrical portion permitting relative rotation between the gear and said shaft in a second position of the shaft, and a latch pivoted on said housing and adapted to engage a reduced portion on said reduced cylindrical portion to retain the shaft in said second position.

2. In a washing machine, a housing, a driving gear in said housing, an axially shiftable driving shaft having a square portion engaging a square aperture in said gear, said shaft also having a circumferential groove, a reduced cylindrical portion on said shaft adapted to disengage said gear when said shaft is axially shifted, an impeller mounted on said shaft, and a latch pivoted to said housing and adapted to engage said groove to retain said shaft in axially shifted disengaged position.

3. In a washing machine, a moving impeller provided with an axial aperture, an inwardly extending shoulder at the lower end of said aperture, a bearing plate, a hub integral therewith and adapted to extend into said aperture, said hub being provided with a peripheral groove, and a spring ring seated in said groove and adapted to bear against said shoulder for retaining the hub in the aperture.

4. In a washing machine, an impeller, a continuously operating gear having a non-circular aperture therethru; an axially-shiftable, non-circular driving shaft threaded thru said non-circular aperture and secured at its lower end to said impeller; said shaft being provided with a cylindrical portion of reduced diameter adapted in one position of said shaft to register with the aperture in said gear to permit relative rotation of said gear and shaft; and means for retaining said shaft in said one position.

5. A washing machine having a stationary bottom, a moving impeller adjacent said bottom provided with an axial aperture extending therethru, a driving shaft extending into

the upper end of said aperture, a bearing plate for stationary bearing on said bottom, and a hub integral with said plate adapted to be received by either end of said aperture and to serve as a thrust bearing for said driving shaft.

6. In a washing machine including a receptacle having a stationary bottom, a drive shaft, an impeller engaged with said drive shaft, and a separate bearing device engaged with said impeller, said bearing device normally resting upon the bottom of the receptacle to be lifted when the impeller is lifted.

7. In a washing machine including a receptacle having a stationary bottom, a drive shaft, an impeller engaged with said drive shaft, and a bearing device normally resting upon the bottom of the receptacle to serve as a thrust bearing for the impeller, said bearing device being engaged with said impeller to be lifted when the impeller is lifted and to be removable therefrom.

In testimony whereof, I have hereunto set my hand.

WILLIAM H. KLEINHAMMER.
